UNITED STATES PATENT OFFICE

112,410

DESIGN FOR A COMBINED PHOTOGRAPHIC COPYING AND PROJECTION APPARATUS

Roy S. Hopkins, Rochester, N. Y., assignor to
Eastman Kodak Company, Rochester, N. Y., a
corporation of New Jersey

Application May 18, 1938, Serial No. 77,267

Term of patent 14 years

To all whom it may concern:

Be it known that I, Roy S. Hopkins, a citizen
of the United States, residing at Rochester, in
the county of Monroe and State of New York,
have invented a new, original, and ornamental
Design for a Combined Photographic Copying
and Projection Apparatus, of which the following
is a specification, reference being had to the
accompanying drawing, forming part thereof and
in which:

Fig. 1 is a plan view;

Fig. 2 is a front view; and

Fig. 3 is a perspective view of a combined
photographic copying and projection apparatus
also showing my design.

I claim:

The ornamental design for a combined photo-
graphic copying and projection apparatus, as
shown.

ROY S. HOPKINS.
